CURLER

John H. Thompson, Glendale, Calif., assignor to
Ross M. McFadden, Glendale, Calif.

Application July 10, 1934, Serial No. 734,443

6 Claims. (Cl. 132—41)

This invention relates to curlers of the type wherein hair is adapted to be coiled about a portion thereof and thereafter clamped until the hair is dry. The particular curler permits the hair to "air dry" as distinguished from the type of curler wherein external heat is applied thereto.

The invention has for an object the provision of a curler which may be easily applied to the hair by the non-expert operator and which will give a professional curl.

The invention has for a further object the provision of a curling device which will quickly, efficiently and artistically produce curls.

A further object is the provision of a curler which is inexpensive in cost of manufacture and equally inexpensive to produce, which is positive in operation, efficient in actual use and service and generally superior to air drying type of curlers now known to the inventor.

The invention further contemplates a curler incorporating many features of construction which render the curler positive in its action, not liable to injure the hair, and assures direct air contact with the hair being curled at all times.

Other objects and features of the invention will be pointed out as the device is described in the body of the specification.

With the above and other objects in view, the invention consists in the novel and useful provision, formation, construction, association, and interrelation of parts, members and features, all as shown in a certain embodiment in the accompanying drawing, described generally, and more particularly pointed out in the claims.

In the drawing:

Figure 1 is illustrative of my curler actually engaging hair for the purpose of curling the same.

Figure 2 is a perspective view of my curler in one position,

Figure 3 is a plan view showing the curler in a second position,

Figure 4 is a top plan view of the invention, the clip member being swung to one position,

Figure 5 is a view similar to Figure 4, the clip being in a second position,

Figure 6 is an end elevation of the invention, and,

Figure 7 is a view taken on the line 7—7 of Figure 5.

Referring now with particularity to the drawing, the improved curler is designated as an entirely by the numeral 1 wherein I have provided a pair of arms 2 and 3 interconnected by a curved end piece 4 of spring-like formation whereby the

said arms are normally urged into separated condition, as shown in Figure 2. It will be noted that the arms and curved end piece are integrally formed and that each arm throughout the longitudinal length is V-shaped in cross section.

A plurality of perforations 5 extend longitudinally of each arm and along what might be termed the apex 6 thereof. The curved end piece 4 functions in the capacity of a resilient hinge and the size is sufficient to accommodate ends of a clamp 7. This clamp constitutes a piece of spring wire-like material, sides of which are bowed at 8 and 9, with an interconnecting curved portion 10 between said sides, and the ends of which are angularly bent, as shown at 11 and 12. The end piece 4 is provided with a pair of off-center perforations shown at 13 and 14, and the ends 11 and 12 are passed through the perforations and within the curved end piece 4. Thus, the ends may be separated to a certain extent, as indicated by the dotted line position 15 of the clamp shown in Figure 3 without the ends being entirely removed from the openings or perforations in the said clamp.

The operation, uses and advantages of the invention are as follows:

The clamp is first moved to say the position shown in Figure 2 whereby ends of the hair may be inserted between the arms. The two arms may then be closed together by the operator and the hair curled around the two arms. This may be accomplished by bodily rotating the curler. After sufficient hair has been coiled about the arms, the clamp may be swung to position so that the end portion 10 will engage the ends of the arms, as illustrated, for instance, in Figures 3 and 5 as well as in Figure 1. It will be observed that the hair gripped between the two arms has direct air contact through the medium of the perforations 5 and further that due to the transverse V longitudinally extending throughout the length of the arms, air is permitted to flow along the arms and through the said perforations 5. Thus, there is air contact with the hair both inside of the curler as well as exterior the curl.

The curlers may be left in position as long as desired or until the hair is dry. I do not specify any particular fluid to be used upon the hair, as water is sufficient although "bandoline" and other articles may be used as desired. After the hair is dry, the clip may be swung from its hair-engaging position to say the position shown in Figure 2 and the arms withdrawn from the center of the curl. If a large curl is desired, it is evident by viewing Figure 3 that the arms will expand to

accommodate the curl. The transverse V given both arms acts as an effective interlock for the end 10 of the clamp and assures that the clamp will not come loose while holding the curl.

5 It is believed that this invention is novel in that a large air contact space is provided for the curl. Thus, when the two arms are held in cooperation, as shown for instance in Figure 3, there are four transverse V's extending longitudinally, 10 it being observed that two parallel V's are formed by the contiguous sides of each arm.

15 It is obvious that various changes and modifications and variations may be made in practicing the invention in departure from the particular showing of the drawing and the specification, all without, however, departing from the true spirit of the invention as defined by the scope of the appended claims.

I claim:

20 1. As a new article of manufacture, a hair curler comprising a pair of arms, a loop portion interconnecting said arms at one end, both arms being substantially V-shaped in cross section throughout their length and disposed with their apexes opposed, and a clamp pivotally secured to said loop and adapted to embrace both arms when the arms are in closed position.

25 2. As a new article of manufacture, a hair curler comprising a pair of arms substantially V-shaped in cross section throughout their length and disposed with their apexes opposed, a loop 30 interconnecting said arms, a resilient clamp rotatively secured to said loop portion and adapted

when swung to one position to parallel the open sides of said arms and engage the outer edge of both said arms between the V portions thereof.

3. As a new article of manufacture, a hair curler comprising a pair of arms substantially V-shaped in cross section throughout their length and disposed with their apexes opposed, a loop 5 interconnecting said arms, a resilient clamp rotatively secured to said loop portion and adapted when swung to one position to parallel the open 10 sides of said arms and engage the outer edge of both said arms between the V portions thereof, both of said arms being provided with through perforations along the apexes thereof.

4. As a new article of manufacture, a hair 15 curler comprising a metal strip looped intermediate its ends and extended to form hair receiving arms, each of said arms being substantially V-shaped in cross section throughout its length 20 with the apexes thereof opposed, and a clamp pivoted to the loop and adapted to embrace the arms.

5. As a new article of manufacture, a hair curler comprising a pair of separable arms hinged together, said arms being formed with longitudinally extending concavities reversely arranged 25 so their inner faces are diametrically opposed.

6. As a new article of manufacture, a hair curler comprising a pair of hinged arms, both arms being substantially V-shaped in cross section 30 throughout their length and disposed with their apexes opposed.

JOHN H. THOMPSON.
